G. A. BRYAN

LIQUID FUEL BURNER

Filed June 18, 1921

UNITED STATES PATENT OFFICE.

GEORGE ALFRED BRYAN, OF PERU, INDIANA, ASSIGNOR TO BRYAN HARVESTER COMPANY, A CORPORATION OF NEW MEXICO.

LIQUID-FUEL BURNER.

Application filed June 18, 1921. Serial No. 478,682.

To all whom it may concern:

Be it known that I, GEORGE A. BRYAN, a citizen of the United States, residing at Peru, in the county of Miami and State of Indiana, have invented certain new and useful Improvements in Liquid-Fuel Burners, of which the following is a full, clear, and exact description.

My invention relates to fuel oil burners and embodiments of my invention are well adapted for use in connection with small steam generator units, such for instance as are used on steam automobiles, tractors and the like. More particularly my invention relates to the atomizing type of burner as distinguished from the vaporizing type.

Generally stated, the object of my invention is to provide means for burning the fuel with the utmost efficiency. To this end my invention aims to obtain a thorough mixture of the fuel and air or other oxidizing fluid in such proportions as to obtain complete combustion. Other objects are economy in operation and simplicity in construction. Still other objects and advantages of my invention will appear from the following description.

In accordance with my invention I deliver the oil under pressure in finely divided form into a chamber in which a regulated amount of air is being introduced under pressure, and in order to cause a thorough intermingling of the air and spray of fuel, I shield the spray from the direct blast of air by enclosing it within a member, preferably conical in shape, which has its sides partially cut away. The air is set into a whirl by being deflected by the curved sides of the mixing chamber, and the intimate mixture thereby resulting is ignited and passes into the combustion chamber with which the mixing chamber communicates.

To atomize the fuel satisfactorily, I employ an atomizer so constructed that just before the fuel passes out of the nozzle opening, it is delivered at high speed and in an oblique direction into a chamber just behind the nozzle opening. The fuel is thereby given a rotative motion with the result that it spreads in all directions in the form of a fine spray as it emerges from the nozzle opening. The oblique direction is obtained by

two small eccentric holes drilled through a closure just back of the nozzle and extending spirally relative to each other. The fuel thus enters the chamber at increased speed and with a whirling motion.

I shall now describe the illustrated embodiment of my invention and shall thereafter point out my invention in claims.

Fig. 1 is a longitudinal section of a complete furnace with my improved burner associated therewith.

Fig. 2 is a detail in sectional elevation of the atomizer.

Figs. 3 and 4 are enlarged details of the parts constituting the nozzle construction of the atomizer.

The furnace shown in cross-section in Figure 1 is generally of the construction disclosed in my co-pending application Serial Number 475,989, filed June 8, 1921. It is of the vertical down-draft type and comprises a mixing chamber 1 at the top and a combustion chamber 2 having an opening 3 at its bottom through which the gases of combustion pass to the boiler 4, the general outline of which is indicated by dotted lines. The mixing chamber and top of the combustion chamber are preferably substantially round in cross section, the latter being distorted or flared laterally at the bottom to conform to the size of the boiler housing. The combustion chamber has an outer sheet metal casing lined with suitable heat insulating and refractory material, such as asbestos and fire brick.

The casing 5 of the mixing chamber is preferably approximately dome shaped and is composed of sheet metal with its bottom edge secured suitably to the top of the walls of the combustion chamber. The casing 5 has in its rear side an opening 6 to which is connected a fan or blower 7 for directing air into the mixing chamber. An atomizer 8 for the fuel oil enters an opening in the top of the casing 5, being supported by a suitable lug 9. Secured to the top of the casing 5 and surrounding the atomizer 8 in axial alignment therewith is a frusto-conical shield member 10 which extends in front of the opening 6 substantially to the bottom of the mixing chamber. This shield member is partially cut away at the bottom

on its two sides out of line with the opening 6, with the result that the spray of fuel from the nozzle of the atomizer 8 is shielded from the direct blast of air, while at the 5 same time the current of air, striking against the curved wall of the dome 5, is set into a whirl, and with this movement comes into contact with the spray through the lateral openings in the shield; thereby producing a 10 very thorough mixing. The combustible mixture is initially ignited by any suitable means, a spark plug 11 being indicated for this purpose in the illustrated construction. The mixture is completely burned in its passage 15 through the combustion chamber, the gases of combustion then passing through the opening 3 into contact with the boiler surfaces.

Any suitable system may be employed for 20 controlling the rate of which fuel and air are delivered to the mixing chamber. If, for example, a pump be employed to supply the oil under pressure to the atomizer, the pump may be directly connected to the 25 blower 7, the connections being so arranged that the supply of air and oil is constant and so proportioned as to give the best rate of combustion with atomizing burners.

The construction of the atomizer 8 is 30 shown in detail in Figure 2. It has a hollow hexagonal body 12 screw threaded at its lower end, and having the nozzle elements held against its lower end by a nut 13, which is shown as round at its upper portion 35 where it fits into the opening in the top of the dome 5, and hexagonal at its lower end to accommodate a wrench. A screw threaded hole is tapped into the body member 12 near its top to receive a screw 14, 40 which serves to attach the nozzle to the lug 9 by engagement, in a vertical slot in the lug. The body member 12 is also provided with a screw threaded lateral bore communicating with the upper end of its hollow 45 interior for receiving a nipple 15 for attachment to the fuel line.

The nozzle elements consist of an inner 50 cup shaped disc 16 and an outer nozzle disc 17. The inner disc 16 fits against the end of the body member and is provided with two oppositely disposed obliquely extending small bores or openings 16' extending in opposite directions or spirally with respect to each other. As shown they extend clockwise 55 and are disposed at the outer edge of the inner periphery of the cup. The central portion of the outer face of the disc 16 is also shown as slightly recessed, the recess being of sufficient diameter to include the 60 outlet ends of the openings 16'.

The nozzle disc 17 is provided with a minute central nozzle opening and is held by the nut 13 against the outer face of the disc 16. The inner face of the disc 17 is 65 also concaved, thereby forming a chamber

18 of a size to include the openings 16'. The outer end of the nut 13 is provided with a flared opening as shown.

The oil under pressure enters the interior 70 of the atomizer through the nipple 15 and passes obliquely through the restricted openings 16' into the chamber 18. It is thereby given a rotative impetus at high speed and emerged from the nozzle opening in the disc 17 in the form of a fine spray. 75

It is obvious that various modifications 80 may be made in the construction shown in the drawings and above particularly described within the principle and scope of my invention.

I claim:

1. A fuel oil burner comprising a mixing chamber having an opening in one side for the admission of oxidizing fluid, an atomizer for the fuel oil entering an end of the mixing chamber, means for directing oxidizing fluid under pressure into the opening in the side of the mixing chamber, and a shield member surrounding the atomizer and extending in front of the opening in the side 90 of the chamber, a portion of the two opposite sides of the shield member in the line transverse that of the opening in the side of the chamber and extending substantially above the plane of the bottom of the opening being cut away. 95

2. A fuel oil burner comprising a mixing chamber having an opening in one side for the admission of oxidizing fluid, an atomizer for the fuel oil entering an end of the mixing chamber, means for directing oxidizing fluid under pressure into the opening in the side of the mixing chamber, and a frustoconical shield member surrounding the atomizer with its small end and extending 100 in front of the opening in the side of the chamber, a portion of the two opposite sides of the shield member in the line transverse that of the opening in the side of the chamber and extending substantially above the plane of the bottom of the opening being 105 cut away. 110

3. A fuel oil burner comprising a substantially dome shaped mixing chamber having an opening in one side for the admission of oxidizing fluid, an atomizer for fuel oil entering the closed end of the chamber, and a shield member surrounding the atomizer nozzle in axial alignment therewith and extending in front of the opening for oxidizing fluid, the shield member being cut away on its two sides in the line transverse to that of the opening in the side of the chamber from its bottom upward to a point substantially above the plane of the bottom 115 of said opening. 120

4. An atomizer for fuel oil and the like comprising a hollow body member having at one end an inlet for the fuel oil, a transverse partition forming a closure for the 130

other end and having therethrough two eccentric restricted openings substantially at the juncture of the disc with the internal wall of the body member extending in the same circumferential direction at an angle to the axis of the body, and a nozzle disc in front of the partition and provided with a substantially concentric restricted open-

ing, the inner face of the nozzle disc being concaved to form a chamber of substantially 10 the diameter of the hollow interior of the body member with which the openings through the partitions communicate.

In witness whereof, I hereunto subscribe my signature.

GEORGE ALFRED BRYAN.
